To all whom it may concern:

Be it known that I, Walter J. Kiefer, a citizen of the United States, residing at Belvidere, in the county of Boone and State of Illinois, have invented a new, original, and ornamental Design for a Shampoo Bowl, of which the following is a specification, reference being had to the accompanying drawings, forming part thereof.

In the drawing:

Fig. 1 is a plan view of a shampoo bowl embodying my new design;

Fig. 2 is a front elevational view thereof;

Fig. 3 is a side elevational view thereof, the opposite side being a mirror image of Fig. 3; and

Fig. 4 is a back elevational view thereof.
The dominant characteristics of the design reside in those portions shown in full lines.

I claim:

The ornamental design for a shampoo bowl, substantially as shown and described.
